UNITED STATES PATENT OFFICE.

MARION R. ZERBE, OF NEW YORK, N. Y.

IMPROVEMENT IN CLASPS FOR LOOPING SKIRTS.

Specification forming part of Letters Patent No. 124,308, dated March 5, 1872.

Specification describing a new and useful Improvement in Clasps for Looping Skirts, invented by MARION R. ZERBE, of the city of New York, in the county and State of New York.

My invention consists of a skirt-clasp for looping up dress-skirts and the like, which is formed of a small plate of metal with a spring, button, and points on each side, so arranged that it will be buttoned to a slight loop or fold of the skirt by one end, and suspended to receive the other fold in the other end, the said folds being secured by turning the buttons over the fold, which is placed on the plate and the points, all as hereinafter described.

Figure 1 is a side elevation of my improved loop-holder with one of the buttons adjusted to the position for applying the loop to the plate and points, to be fastened by turning the bottom back over the lower end of the plate; and Fig. 2 is a side elevation showing the manner of looping the skirt of a dress by it.

A represents the plate, B B' the buttons, and C the points. The two buttons are on opposite sides of the plate, and they are pivoted to opposite ends. The points are in the same relative positions, but they are riveted to the end of the plate, over which the free end of the button on the same side of the plate that the points are swung, and they point toward the pivot of the button. Said buttons

are curved outward from the plate to provide room for the points under them; also for the loop of the dress to be secured, and to have the free ends pinch upon the plate A when adjusted to fasten the loop. The looper thus constructed is suspended from the upper part of the skirt of the dress by fastening to a loop, D, thereof by the upper end of the plate and the button on the back side, and a loop, E, to be fastened up is engaged by the lower end and front button, as shown. The instrument thus holds the loops both by pinching them between the ends of the buttons and the plate and by crowding the loops against the points C, which effectually prevent them from escaping. Care will be taken not to have the points sharp enough to make holes in the dress. The instrument is to be made quite small and light, and may be made of any fine metal and in any ornamental style.

Having thus described my invention, I claim as new and desire to secure by Letters Patent—

A skirt-clasp for looping up garments, consisting of plate A, pivoted spring-buttons B B', and serrated points C C, constructed and combined as and for the purpose described.

MARION R. ZERBE.
